UNITED STATES PATENT OFFICE

THOMAS C. ERSKINE, OF COLUMBUS, OHIO, ASSIGNOR TO UNITED SHOE MACHINERY CORPORATION, OF PATERSON, NEW JERSEY, A CORPORATION OF NEW JERSEY

GAUGE

Application filed May 2, 1928. Serial No. 274,617.

This invention relates to gauges for use in machines for operating upon shoes and particularly those in which the shoe is presented to the action of an operating tool by 5 a progressive movement.

While many features of the invention may be employed advantageously in any shoe machines of this type, I have shown it as embodied in a loose nailing machine for inserting 10 nails about the margin of the sole of a shoe. In operating a machine of this character, the shoe is presented by the operator and guided by a gauge in its movement beneath the awl and driver which act to perforate the sole, feed it in a step-by-step manner and drive a nail in each perforation as 15 it is brought into nailing position. In this operation, it is important to locate the nails uniformly and accurately from the edge of the sole, particularly about the heel-seat, in 20 order that the flange of the counter may be properly secured and that the nails may not be exposed in the rand crease after the heel-seat has been trimmed. This necessitates holding the shoe firmly against the gauge 25 and in some cases, particularly in handling shoes of delicate leather, an objectionable mark has been made by the gauge about the counter of the shoe.

In one of its aspects, the present invention 30 consists in a gauge including in its organization a guard member of novel construction, by the use of which all danger of marking the shoe is obviated and the operator enabled 35 to present the shoe rapidly to the machine and hold it firmly against the gauge without danger of marking or disfiguring the surface 40 of the leather. I have found that this desirable result may be secured by employing a guard member of flexible and yieldable material arranged to travel between the gauge and the work, serving as a cushion and moving with the work so as to eliminate relative movement between the work and the 45 gauge.

A form of gauge which has been employed to some extent in loose nailing machines includes a pair of spaced rolls mounted for free rotation and adapted to run in the rand crease of the shoe as it is presented to the machine. This gauge has proved very satisfactory in its shoe positioning and guiding functions but the danger of marking is accentuated in its use on account of the tendency of the feeding tool to crowd the shoe 50 against the gauge rolls. This condition has prevented the extended use of the two-roll gauge. In another of its aspects, accordingly, the present invention consists in the development or improvement of the two-roll gauge with a view to eliminating the defect noted by providing a guard member to travel 55 between the shoe and the acting faces of the gauge rolls.

Preferably, the guard member will be of the endless type, as with such construction the desired travel of the guard is most conveniently secured, wear is equalized and the action of the gauge rendered uniform in extended use. As herein shown, therefore, a 60 flexible and yieldable disk is employed and this is so located that its margin is at all times interposed between the acting face of the gauge member and the surface of the shoe being operated upon.

These and other features of the invention will be best understood and appreciated from the following description of a preferred embodiment thereof, selected for purposes of illustration and shown in the accompanying drawings, in which

Fig. 1 is a view in side elevation showing a portion of a loose nailing machine equipped with the gauge of my invention;

Fig. 2 is a view in perspective, on an enlarged scale, showing a portion of a shoe in operative relation to the gauge;

Fig. 3 is a sectional view illustrating the mounting of the guard disk; and

Fig. 4 is a view in perspective illustrating a modified form of gauge.

The loose nailing machine comprises a head in which is mounted a cam shaft and cams for operating an awl bar 12 carrying an awl 14 and a driver bar carrying a driver 16. As will be apparent from Fig. 2, the awl is operated first to perforate the sole of the shoe and then move transversely, feeding the work and carrying the awl hole into alignment with and beneath the driver 16. The driver is then operated to insert a nail in the awl hole and the operation continued in a step-by-step manner about the margin of the heel-seat and sometimes about the entire sole. The machine includes a throat plate 20 which bears upon the surface of the work and a transversely movable slide 18 which carries the gauge mechanism and which may be shifted by segment and gear mechanism when it is desired to vary the distance between the margin of the sole and the line of nails as, for example, in passing from the shank of a shoe to the heel-seat portion thereof.

The gauge mechanism is directly mounted on a gauge slide 22, held in place by a pair of vertically disposed headed studs 24 and having rack teeth cut in its upper surface which mesh with a pinion 28 upon a transverse shaft which may be connected to a lever, not shown, or any other convenient means by which the pinion may be turned to shift the gauge slide forwardly and rearwardly to make an initial adjustment of the gauge mechanism. It will be understood that this adjustment is made preliminarily to operating upon shoes of a given style and then not ordinarily disturbed, whereas the adjustment of the slide 18 above mentioned is commonly made during the progress of the work about each individual shoe.

The gauge slide 22 has a pair of downwardly extending ears between which extend a journal pin 26, upon which is pivotally mounted a three-arm lever. The forwardly extending arm 30 of the lever carries a gauge roll plate 36 having a downwardly extending stem, which is clamped in the lever by a clamping bolt 31, and a pair of freely rotating gauge rolls 38 mounted upon its upper surface upon spaced parallel axes. These rolls are the gauge members which serve primarily to guide the shoe with respect to the awl and driver and it will be apparent that if the gauge is displaced rearwardly, as seen in Fig. 2, the line of nails will be spaced further from the margin of the sole, and vice versa.

The lever is yieldingly maintained in place by a vertically disposed pin 40, which passes freely through an aperture in the second arm 32 of the lever. The pin 40 has a head which is received in a recess in the upper surface of the gauge slide and provided at its lower

end with an adjusting nut 42. Between the gauge slide and the arm 32 of the lever is disposed a compression spring 44 which normally holds the arm of the lever against the nut 42. By turning this nut, the initial position of the lever may be varied and the gauge rolls moved nearer to or further from the throat plate 20.

The third cam 34 of the lever extends rearwardly and obliquely and is provided at its outer end with a journal pin 54. This has a threaded stem and is securely maintained in the arm 32 by a clamping bolt 58. Journaled for free rotation on the pin 54 is a conical head, comprising a body portion 48 and a cushion ring 50. The guard member comprises a large disk of leather or other tough but flexible and yieldable material. This is clamped upon the conical head by a washer 52 and is, consequently, free to travel about the axis of the journal pin 54. The journal pin is recessed, as shown in Fig. 3, and provided with a spring 56 which acts to hold the material of the guard disk 46 off the end of the journal pin so as not to retard the free rotation of the guard disk.

The guard disk 46 is of such size and its axis so located with respect to the gauge rolls 38 that the margin of the disk is bent upwardly over the acting peripheral faces of the gauge rolls and covering the upper edges thereof. If grain leather is used as the material of the guard disk, the flesh side is preferably disposed toward the gauge rolls and the grain side toward the work. The margin of the disk 46, therefore, bridges the space between the gauge rolls 38 and serves as an endless traveling cushion between the gauge rolls and the work. The disk itself is turned by the pressure of the moving shoe upon it and it, in turn, rotates the gauge rolls. The guard, therefore, not only eliminates relative movement between the work and the gauge but serves as a cushion to receive the impression of any slight irregularity, such as the back seam, which otherwise might momentarily displace the work as it passed over the face of a rigid gauge roll.

The gauge rolls shown in Fig. 2 are mounted on two axes spaced a fixed distance apart. In handling shoes of various sizes, however, it is sometimes convenient to change the spacing of the gauge rolls. In Fig. 4 I have, accordingly, shown a construction in which provision is made for relative adjustment of two gauge rolls. Referring to Fig. 4, each gauge roll 138 is mounted upon the forward end of a separate lever 136, pivotally mounted upon a pin 137 set in one arm 130 of a lever intended to be mounted on the gauge slide as before. Each lever 136 is forked at its rear end and provided with a swivel block 140. The blocks 140 are threaded to receive a right and left-hand screw 130

142, which is retained in place by a central collar 144 received in a depression in a portion of the arm 130 and having at its outer end a knurled head 146. This may be turned to swing the rear ends of the levers 136 toward or from each other and so adjust the spacing of the gauge rolls 138. The guard disk 46 is embodied in this construction in the manner already explained.

It will be apparent that in the normal operation of the machine the guard disk 46 is rotated so that its margin has the same linear travel as the work. A fresh portion of its material is, therefore, constantly brought into operative position, with the result that wear is reduced to a minimum and is equally distributed when it does occur, so that uniform action and long life of the gauge is insured. Moreover, the disk may be readily replaced should that become necessary.

Having thus described my invention, what I claim as new and desire to secure by Letters Patent is:

1. In a machine for operating on shoes, a rotatable gauge roll for guiding a shoe with respect to an operating tool, and an endless guard member movable with the shoe and between the shoe and said gauge roll.

2. In a machine for operating on shoes, a freely rotatable tapered gauge roll for guiding a shoe with respect to an operating tool, and an endless guard member of flexible material movable continuously between the shoe and said gauge roll.

3. In a machine for operating on shoes, a rigid gauge roll freely rotatable and located for guiding a shoe with respect to an operating tool, and a guard member of yieldable material movably supported in position between said roll and the shoe, serving to cushion small irregularities in the contour of the shoe, being moved by engagement with the shoe to present continually a fresh portion and acting itself to rotate the gauge roll.

4. In a machine for operating on shoes, a rotatable gauge roll for guiding a shoe with respect to an operating tool, and a disk of flexible material mounted for movement about an axis so disposed that the margin of the disk is bent over the acting face of the roll and travels continuously between the roll and the shoe.

5. In a machine for operating on shoes, a gauge member for guiding a shoe with respect to an operating tool, a yieldingly movable supporting member for said gauge member, and a flexible guard member carried also by said movable supporting member and arranged to travel continuously between the shoe and said gauge member.

6. In a machine for operating on shoes, a gauge roll mounted to rotate about an

axis disposed at one side of the operating tool, and a disk of flexible material mounted to turn about an axis located beyond that of the gauge roll and on the same side of the operating tool.

7. In a machine for operating on shoes, a carrier mounted for movement toward and from the operating tool, a gauge member carried thereby and acting to guide a shoe with respect to the operating tool, and an endless guard member of flexible and yieldable material mounted also on said carrier, movable therewith and traveling continuously between the shoe and said gauge member thereby protecting the shoe from disfigurement by the gauge member.

8. In a machine for operating on shoes, a transversely movable slide, a three-arm lever mounted therein for yielding movement, a gauge roll mounted on one arm of said lever, spring position controlling means associated with a second arm thereof, and a flexible guard disk pivotally mounted upon the third arm.

9. In a machine for operating on shoes, a pair of gauge rolls freely rotatable on spaced axes located in predetermined relation to an operating tool, and a guard disk of flexible material mounted for movement about an axis so located as to maintain a portion of the margin thereof continuously upon the acting faces of the gauge rolls.

10. In a machine for operating on shoes, a pair of gauge members located in predetermined relation to an operating tool, and a guard disk of flexible material mounted for movement about an axis so located as to maintain a portion of the margin thereof continuously in position to bridge the space between said gauge members.

11. In a machine for operating on shoes, a pair of gauge rolls freely rotatable on spaced axes and bodily adjustable for varying spacing, and a guard member of flexible material disposed between the gauge rolls and the work and overlapping the acting faces of said rolls in all adjusted positions thereof.

12. In a machine for operating on shoes, a pair of tapering gauge rolls with flat upper surfaces adapted to underlie the edge of a projecting sole and guide a shoe with respect to an operating tool, means for adjusting the separation of said rolls to accommodate shoes of various sizes, and a leather guard disk arranged to turn with a portion of its margin between the shoe and the acting faces of said rolls in all adjusted positions thereof.

13. A machine of the class described comprising a pair of spaced gauge rolls arranged to guide a shoe by engagement with its curved contour, fastener inserting means, a feeding tool movable in a straight line path and tending to crowd the shoe always

against one of said rolls, and a guard of yieldable material arranged to travel always between the shoe and the gauge rolls to obviate marking of the shoe thereby.

14. A nailing machine comprising spaced gauge rolls arranged to guide a shoe, an awl for perforating the sole and feeding the shoe in a step-by-step manner tending to crowd the shoe always against the gauge rolls, a driver, and a guard disk arranged with its edge traveling between the shoe and the gauge rolls to cushion the engagement of the shoe therewith.

15. In testimony whereof I have signed my name to this specification.
